MUSIC BOX ATTACHMENT FOR VENDING MACHINES

Weldon G. Bowlus, Dallas, Tex.

Application August 13, 1951, Serial No. 241,652

6 Claims. (Cl. 84—94)

1

This invention relates to vending machines and more particularly to an attachment for such machines adapted to produce music during the operation of vending merchandise from such machines.

The principal object of the invention is to provide a Swiss music box attachment for various types of coin operated vending machines, especially the type generally designed for vending salted peanuts, candies and the like, said attachment being calculated to stimulate interest in the vending machine to which it is attached, to result in increase in sales from the machine.

Another object of the invention is to provide a music box attachment which is both economical and simple and designed for installation in a vending machine in a minimum of time by unskilled persons without requiring special tools.

Broadly, the invention consists of a conventional Swiss music box so arranged in relation to the vending machine as to possess maximum audibility and whose winding shaft is connected in such manner to the operating handle of the vending machine that the spring of the music box can be wound each time the operating handle is actuated. Moreover, provision is made to preclude overwinding of the music box spring and possible damage to the music box, the spring being wound a predetermined degree during each operation of the vending machine. Hence, it is not possible to increase the tension on the music box spring beyond a predetermined degree even if the vending machine is operated a number of times successively at closely spaced intervals.

With the foregoing objects in view, the invention has further reference to certain features of accomplishment which will become apparent as the description proceeds, taken in connection with the accompanying drawings wherein:

Figure 1 is a vertical sectional view of a conventional vending machine in which the invention is shown installed.

Figure 2 is a detail perspective view of the winding tube and head.

Figure 3 is a view in transverse section taken on line 3—3 of Figure 1.

Figure 4 is a plan view of the conventional vending wheel.

Figure 5 is a transverse sectional view of a conventional vending machine showing a bottom plan view of a modified form of the invention.

Figure 6 is a fragmentary view in vertical section taken on line 6—6 of Figure 5, and

Figure 7 is a perspective view of the cam track forming a part of the modified form of the invention shown in Figures 5 and 6.

Continuing with a more detailed description of the drawing reference numeral 10 denotes generally the housing of a conventional machine for vending commodities such as peanuts, candies and the like. This housing is made up of the upper and lower sections 11 and 12, respectively, the upper section having windows 13 to reveal the merchandise in the machine. The two sections 11 and 12 are held in fixed relationship by means of an axial rod 14 which extends from the top to the bottom of the machine housing 10, the lower end of which is provided with a head 15 and, by virtue of a square portion 16, is held non-rotatably in an aperture in the bottom 17 of the lower section 12.

While the music box attachment of the present invention may be designed for application to various types of vending machines, the present adaptation is as shown and occupies a position below the top plate or cover of the vending machine. In this position, maximum audibility is made possible. The music box 18 is interposed between the conventional cover or top 19 of the machine and a plate 20 which latter is composed of wood to prevent damping of the sound emitted by the music box 18.

To facilitate installation of the attachment in or on the vending machine, the elements making up the attachment are assembled together and held in fixed relationship so that they can be attached to the vending machine as a unit. These elements consist of a plate 21 which is provided with side flanges 22 adapted to embrace the top of the upper housing section 11. The plate 21 is perforated and dimpled as at 23 to effect relative spacing between plate 21 and wooden plate 20. A weather housing 24 embraces the music box 18 but only partially covers the area of the wooden plate 20, to which it is attached by means of bolts 25, which bolts also secure the wooden plate 20 to the lower plate 21. The housing 24 has no bottom to interfere with the transmission of sound from the music box 18, which is secured directly to the wooden plate 20. The housing 24 is also without a top other than the cover 19, whose flange 26 extends part way around the housing 24 at one side of the machine. A wooden filler block 27 is disposed under the cover 19 at the side opposite the housing 24 and is secured to the wood plate 20 and underplate 21 by bolts 28, which extend through the block 27 and plates 20 and 21, thus holding all of these elements in fixed relationship.

The cover plate 19 is secured to the underplate 21 by means of a sleeve 29. The upper end of the sleeve 29 is internally threaded to engage the

threads 30 on the barrel 31 of the lock cylinder 32. The lock cylinder 32 is internally threaded, as shown in dotted lines in Figure 1, to receive the threaded upper end of the rod 14, which, as stated, extends axially through the machine. By inserting a key into the lock cylinder 32, the latter may be disengaged from the barrel 31 and rotated to effect disengagement of the lock cylinder with the rod 14, whereupon the cover plate 19 may be removed, along with the music box attachment, consisting of the elements 20, 21, 24 and 27, inasmuch as the sleeve 29 secures these elements together by virtue of its threaded lower end and the nut 33 which is attached to the threaded lower end and which bears against the underside of the lower plate 21.

The winding shaft 34 for the spring which operates the music box 18 extends through openings in the wooden plate 20 and the underplate 21. The extended end of the winding shaft 34 has 20 a transverse opening in which is mounted an actuating arm 35. This arm is adapted to be swung on an arc of approximately 180 degrees by means of a winding head 36 which, for reasons to be explained presently, is substantially triangular in shape and is provided with right-angular fingers 37 at each of its three angles—the fingers being adapted to successively engage and move the operating arm 25 of the winding shaft 34. The winding head 36 is affixed to the upper end of a tube 38, the latter embracing the rod 14 to a point below its mid-section. The lower end of the tube 38 is made into triangular form as at 39, to be received by a correspondingly shaped recess 40 in the hub 41 of a vending wheel 42, as shown in Figure 4 and which is a part of the conventional vending machine.

Vending wheel 42 is provided with a multiplicity of radial fingers 43 which are engaged by a toothed wheel 44, mounted on a shaft 45 which extends through the front wall of the vending machine. An operating knob 46 is mounted on the outer end of the shaft 45 and whose function is to rotate the wheel 44, which in turn rotates the vending wheel 42, to bring into successive register with the mouth 47 of the chute 48 the several openings 49 of the vending wheel 42. The quantity of peanuts or other merchandise entrapped in each of the openings 49 of the vending wheel 42 constitutes the quantity delivered into the receptacle 50 following the insertion of a coin and the operation of the handle 46.

The purpose in making the winding head 36 triangular and the lower end of the tube 38 of corresponding shape is two fold. Primarily, the fingers 37 are pre-disposed in relation to the winding arm 35 to insure against displacement of this arm beyond 180 degrees from its starting point predetermined by the stop 51, against which it comes to rest following the operation of the music box. The triangular form of the winding head and the lower end 39 of the tube 38 makes it impossible for the operator to improperly install this element.

Presence of the invention on the vending machine does not interfere with its normal operation nor does it alter in any way the normal operation of filling the machine since the cover 19 is removed in the usual manner to gain access to the upper section 11 of the machine, although in the present case, the music attachment is removed along with the cover 19.

In Figures 5, 6 and 7 is shown a modified form of the invention. The music box 52 is mounted on a wooden plate 53, the latter, in turn, being

mounted on an underplate 54 which is provided with a flange 55 adapted to embrace the top of the upper section 56 of the vending machine, fragmentarily shown in Figure 6. Housing 57 is interposed between the cover 58 of the machine and the wooden plate 53 at one side and is secured by means of screws 59 to the wooden plate 53, set screws also securing both the housing 57 and the wooden plate 53 to the flanged underplate 54. Opposing the housing 57 is a wooden filler block 60 which is joined to the plates 53 and 59 by means of bolts 61. A sleeve 62 is threaded at its upper end to engage the barrel 63 of the lock 64 which secures the cover 58 to the rod 65, the latter securing the upper and lower sections of the vending machine together.

The sleeve 62 secures the cover 58 and plates 53 and 54 together as a unit so that when the cover 58 is removed, the elements of the music box attachment are likewise removed.

On the underside of the lower plate 54 is a plate 66 having circumferentially spaced legs 67 on its perimeter, these legs having their ends turned at right angles to provide feet 68 which are perforated to receive screws 69 adapted to hold the plate 66 in fixed relationship with the plate 54. The plate 66 has a central opening 70 through which extends the triangularly shaped upper end 71 of a tube 72. The tube 72 extends downwardly and is held in any suitable manner, such as by means of a triangularly shaped lower end in engagement with the correspondingly shaped recesses in the vending wheel of the vending machine, such as shown in Figures 1 to 4. Accordingly, when the vending wheel is rotated, the tube 72 is likewise being rotated.

Mounted on the triangularly shaped portion 71 of the upper end of tube 72 is a disc 73. This disc has a central opening of triangular shape to receive the upper end 71 of the tube 72 and while the disc is rotated by the tube 72, it is free for vertical displacement thereon and is normally urged downwardly by means of a coil spring 74. Struck downwardly from the disc 73 is a series of three fingers 75. When the disc 73 is rotated by the tube 72, the fingers 75 ride up on to cam segment 76 arranged in a circular manner on the plate 66. There are three of these cam segments 76, as representing 100 degrees of the circle and their ends are spaced 20 degrees apart and when the fingers 75 are in elevated positions on the cam segments 76, prongs 77 struck upwardly at circumferentially spaced intervals on the periphery of the disc 73 will be brought successively into engagement with the winding arm 78 mounted on the winding shaft 79 of the music box 52. The length of each cam segment 76 determines the degree of displacement of the winding arm 78. Each cam segment 76 has a gradual rise *a* and an abrupt drop *b*, hence when the fingers 75 reach the end of the cam segments 76, they will ride off the cam segments at their ends *b* under pressure of the spring 74 and the upturned prongs 77 will drop below the plane of the winding arm 78, the prong which is currently engaged with the arm 78 being disengaged therefrom to allow the arm to return during unwinding of the music box spring and will come to rest against the stop 80.

The arrangement shown will enable the winding arm 78 to be moved 180 degrees regardless of the number of times the vending machine is operated in rapid sequence.

Manifestly, the construction as shown and described is capable of some modification and such

modification as may be construed to fall within the scope and meaning of the appended claims is also considered to be within the spirit and intent of the invention.

What is claimed is:

1. In a vending machine having a vending wheel and an operating shaft therefor, a music box attachment for said vending machine comprising vertically spaced and relatively separated non-metallic plates, a spring actuated music box supported on one of said plates and having a spring winding shaft extending therethrough, a winding arm on said shaft, a tubular member detachably supported on said vending wheel and rotatable therewith, a winding head affixed to said winding tube at one end and having a series of circumferentially spaced fingers adapted for successive engagement with said winding arm when said operating handle is actuated and effective to displace said winding arm a predetermined degree to wind the spring of said music box.

2. In a vending machine having a housing in separable sections and a rod joining said sections together, a vending wheel rotatable on said rod, an actuating handle for said vending wheel, a cover for the uppermost section of said housing, a music box attachment for said vending machine comprising a series of metallic and non-metallic plates in fixed relation to said cover, said plates and cover being centrally apertured to receive the upper end of said rod, a spring actuated music box disposed between said cover and one of said non-metallic plates and having a spring winding shaft extending through the lowermost of said plates, a winding arm attached to said shaft, a tube embracing said rod and adapted to be rotated by said vending wheel and means operated by said tube adapted to be brought into successive engagement with said winding arm and effective to wind the spring of said music box a predetermined degree during each operation of said actuating handle.

3. In a vending machine composed of a housing having a cover, a rod extending axially through said housing and cover, a vending wheel rotatable on said rod, an operating handle for said vending wheel, a series of metallic and non-

metallic plates secured together and to said cover for removal from said housing with said cover as a unit, a spring actuated music box attached to one of the non-metallic plates under said cover and having a winding shaft, a winding arm on said shaft and means operated by said vending wheel adapted to be brought into engagement with said winding arm upon each operation of said operating handle to wind the spring of said music box a predetermined degree.

5. In a vending machine composed of a housing in separable sections and provided with a vending wheel and an actuating handle therefor, a music box attachment for said vending machine comprising a group of interconnected and spaced apart plates of metallic and non-metallic material, a spring actuated music box attached to one of the non-metallic plates and having a winding shaft extending through the lowermost of said plates, a winding arm attached to said shaft and means actuated by said vending wheel adapted to be moved against and past said winding arm to wind said music box spring a predetermined degree upon each operation of said vending wheel actuating handle.

15. In a vending machine composed of a housing having a vending mechanism and an operating handle therefor, a music box attachment for said vending machine comprising a plurality of metallic and non-metallic plates joined together as a unit, a spring actuated music box attached to one of said non-metallic plates and having a winding shaft extending through an opening in the lowermost of said group of plates and means actuated by said vending mechanism adapted for periodic engagement and disengagement with respect to said winding shaft to wind the spring of said music box a predetermined degree upon each operation of said operating handle.

20. The structure of claim 5, in which the means actuated by said vending mechanism consists of a plate having circumferentially spaced fingers adapted to be successively advanced against said winding arm.
